DESIGN.

No. 30,317.

J. W. KENNEDY.
FIRE POT LINING SECTION.

Patented Mar. 7, 1899.

(Application filed Feb. 9, 1899.)

UNITED STATES PATENT OFFICE.

JOHN W. KENNEDY, OF ROCHESTER, NEW YORK, ASSIGNOR TO THE SILL
STOVE WORKS, OF SAME PLACE.

DESIGN FOR A FIRE-POT LINING-SECTION.

SPECIFICATION forming part of Design No. 30,317, dated March 7, 1899.

Application filed February 9, 1899. Serial No. 705,116. Term of patent 14 years.

To all whom it may concern:

Be it known that I, JOHN W. KENNEDY, a citizen of the United States, residing at Rochester, in the county of Monroe and State of New York, have invented and produced a new and original Design for a Fire-Pot Lining-Section, of which the following is a specification, reference being had to the accompanying drawings thereof.

10 Figure 1 is a perspective view of my design for a fire-pot lining-section; Fig. 2, a view of the rear side; Fig. 3, an end view, and Fig. 4 a bottom plan view.

15 The leading feature of my design is the shape and configuration of the lining-section adapted to be used in the fire-pots of stoves and ranges.

20 The top of the lining-section is indicated by 1 and the face by 2, the corner connecting them being curved. The top 1 is recessed at 3 at one end on the forward side and upon the rear side forms the overhang or projection 4, having the cut-away portion upon one end, forming the recess 5. The section is 25 formed upon one end with the face 6, arranged

at a slight angle to the face 2, the ridge formed between the faces extending slightly outward at the lower end, the face 2 curving outwardly at 7 to meet it. One end 8 is formed at a slight angle to the face, and the opposite end 30 9 is provided with the curved recess 10 near its upper end, while the lower end is cut away, curving under at 11 to meet the recess 12. The lower edge or bottom of the section is cut away, leaving the projection 13, and 35 also to form the recesses 14 and 15, the latter extending somewhat higher than the former and formed with the shoulder 16 at the end, as shown in Fig. 4. The rear face of the brick is recessed upon the lower portion, as shown 40 at 17, the top of said recess being curved downward upon one end to meet the bottom of the section.

What I claim is—

25 The design for a fire-pot lining-section, substantially as herein described and shown.

JOHN W. KENNEDY.
